UNITED STATES PATENT OFFICE.

EDWIN R. GILL, OF YONKERS, NEW YORK, ASSIGNOR, BY MESNE ASSIGNMENTS, TO
HALL SWITCH & SIGNAL COMPANY, A CORPORATION OF MAINE.

SENDER-BOARD APPARATUS.

1,160,876.

Specification of Letters Patent. Patented Nov. 16, 1915.

Application filed May 25, 1910. Serial No. 563,395.

To all whom it may concern:

Be it known that I, EDWIN R. GILL, residing at Yonkers, in the county of Westchester and State of New York, have invented 5 certain new and useful Improvements in Sender-Board Apparatus, of which the following is a specification.

My present invention relates to a new and improved apparatus for automatically 10 sending selective signals to individual stations of a group, and to a construction of board or support for carrying such apparatus.

An object of the invention is to provide 15 a sending device of the kind mentioned whereby combinations of electrical impulses may be rapidly impressed upon a line with the minimum of attention and liability to error.

20 A further object is the provision of a sending device which may be readily secured in place upon or removed from a board adapted to carry such sending devices, without disturbing or interfering with the operation of other sending devices which may 25 be carried by the board.

30 A further object is to provide means whereby all electrical connections with a newly attached sending device are made co-incident with the act of attaching it.

35 Other objects and aims of the invention, more or less broad than those stated above, will be in part obvious and in part specifically referred to in the course of the following description of the elements, combinations, arrangements of parts, and applications of principles constituting the invention; and the scope of protection contemplated will be indicated in the appended 40 claims.

In the accompanying drawings, which are to be taken as a part of this specification, and in which I have shown a merely preferred form of embodiment of the invention: Figure 1 is a face view of one of the sending devices, detached; Fig. 2 is a side view of the same partly in section and partly broken away; Fig. 3 is a sectional view, partly in elevation, showing a sending device in its relation to a supporting board and cover; Fig. 4 is a detail of the clock work of a sending device, the back plate being removed; Fig. 5 is a face view

of a board carrying a number of sending devices; and Fig. 6 is a similar view, with 55 the cover plate removed.

Considering now one of the sender units, independently of its attachment to the board, the same comprises a suitable frame work 1 of conducting material, supporting 60 a main spring 2 upon main shaft 3, which may be wound up by means of a suitable handle 4 mounted upon shaft 3 well beyond the front of frame 1. A stop-arm 5 is fixed on the shaft 3 so as to turn with it, and said 65 arm has an offset portion 6 which lies normally in the path of a pin 7 on a make-and-break wheel 8. Said wheel 8 is mounted upon a shaft 9 carrying a pinion 10 that meshes with the gear 11 on the shaft 3. 70 Gear 11 is connected to shaft 3 for rotation in one direction as by means of a ratchet-clutch device (see Fig. 4), while shaft 3 may be rotated relatively to the gear 11 in the other direction, which is the 75 direction for winding up spring 2. Rotation of shaft 3 in this latter direction is, however, limited, as by engagement of the stop-arm 5 with a stop-piece 12 on the frame 1. Movement of the make-and-break wheel 80 when released is controlled by the escape-ment 13, or equivalent retarding means, connected to the shaft 9 by a train of gears, sub-stantially as shown.

A long movable contact spring 14 is me-85 chanically and electrically connected to the front plate 28 of the frame 1, and has an angle-piece 15 whose tip extends into the path of movement of the teeth on the make-and-break wheel 8, so that as the latter revolves 90 in the direction of the arrow in Fig. 1, the spring is recurrently lifted into contact with the relatively fixed terminal 16.

Considering how the means whereby the device thus far described may be electrically 95 connected to line, it will be noted that the front and back plates 28 and 29 of the frame 1 in the structure illustrated are rectangular and are spaced apart by means of metallic posts 17, 18, 19, and 20, at the four corners, 100 respectively, diagonally opposite posts 17 and 19 being preferably solid, and posts 18 and 20 tubular. Through the tubular mem-bers 18 and 20 are adapted to extend appropriate pins or bolts, whereby the sending de-105 vices are operatively secured upon a board

21, preferably of insulating material, a plurality of the devices being carried, as shown in Fig. 6. As best shown in Fig. 3, the board 21 is appropriately pierced for each sending device, and pins 22 and 23 are threaded into these apertures, the apertures being spaced to correspond to the positions of the tubular members 18 and 20 respectively. Shoulders 24 and 25 on said pins 10 abut against the forward face of the board as shown, when the pins are screwed into place. The rear ends of the pins behind the board, are formed into a reduced threaded portion 26 and 27, which, by the addition of 15 appropriate clamping members threaded thereon, constitute binding posts, whereby electrical connection between said pins and the line may be established. The opposite or forward end of pin 23 is adapted to enter 20 and snugly fit the tubular member 20 of the sending device with sufficient friction to form a good electrical connection therewith. The pin 23 may extend forwardly beyond the front plate 28 of the frame 1, and be secured by means of a nut threaded upon its 25 end if desired, but this is not necessary. Pin 22, is considerably reduced forwardly of its shoulder 24 and this reduced portion extends into and beyond the tubular member 18 and is separated from the back plate 29 of frame 1, by a ring of insulating material 30 interposed between shoulder 24 and the back plate. The pin inwardly of the shoulder 24 is insulated from the member 18 as by means 30 of an insulating tube 31. Beyond the front plate 28 of frame 1 the pin 22 is separated from the frame by a ring of insulating material 32, while the fixed contact piece 16 is clamped upon the pin as by means of nut 34. 35 By the construction described it will be evident that pin 23 is in direct electrical connection with the metallic frame 1, while pin 22 is insulated therefrom, so that when the poles of a generator are applied to the pins, 40 behind the board 21, current will pass only by way of contacts 14 and 16 as these are recurrently brought together in the operation of the make-and-break wheel 8. The sending devices are readily removable from 45 the supporting board for purposes of repair or substitution, it being only necessary, in the form shown, to take off the nut 34, whereupon the device may be slipped off its pins 22, 23. The pins being held in relatively fixed relation in the board, and the senders all being similar in size and construction, it is obvious that the senders may be easily and quickly slid into position upon the pins and secured by the application of the 50 single nut 34. The operation of bodily removing and replacing any one sender should require only a few seconds, the electrical connections being made without particular attention.

55 Referring now to the guards for the send-

ers, these preferably take the form of disks 35, mounted upon shafts 3, respectively, forwardly of the front plates 28 of the devices. Shafts 3 with their attached handles 4 extend through suitable apertures 36 in a cover 70 37 that is removably held in spaced relation above the board, and each opening 36 is concentrically smaller than the disk 35 of the corresponding sender, a spring 38 surrounding shaft 3 and urging the disk away from 75 the sender in a direction to close the opening 36 when the sender and cover 37 are in position. The apertures 36, while smaller than the disks 35, are larger than the handles 4, so that the cover may be lifted bodily off 80 without the necessity of detaching the handles from their shafts. Rotation of the disk 35 in its own plane is prevented as by means of a headed pin 40 preferably extending from the stop-piece 12 through the disk. 85 Numerals or other marks identifying the individual senders are placed upon the disks so as to be visible through openings 36, and these, by the means last described, are maintained in a constant relation to the operating 90 keys of their respective senders.

It is to be understood that all of the senders upon a board are electrically connected through their pins with a line (not shown) in any usual or preferred manner, so that 95 upon actuation of any one or succession of senders a selective signal or signals, characterized by the particular make-and-break wheels used, may be impressed upon the line.

In operation, when it is desired to call a particular station on the line the operator, selecting the proper sending device on the board, rotates the handle 4 of that sender until the stop 5 engages the pin 12. Upon releasing the handle the spring 2, in returning the handle to its normal position, operates through gear 11 and pinion 10 to rotate the shaft 9, and with it the make-and-break wheel 8. The rapidity of movement of the parts is governed by the train of gears operating the escapement 13. The wheel 8 rotates in the direction indicated by the arrow on Fig. 1 and the teeth on the said wheel come into engagement with angle-piece 15 on the contact spring 14 causing said spring 115 to be recurrently lifted to engage the fixed contact 16. Obviously the number of teeth upon wheel 8 will determine the number of separate contacts made and the circumferential length of the individual teeth will determine the duration of the contact. Thus, supposing the station selected to be that indicated in Fig. 1, the rotation of the wheel 8 will impress five short impulses upon the line followed by a second long impulse, a 120 short impulse, a long impulse, a short impulse, a long impulse, and a final long impulse. It should be mentioned that the final long impulse, in the present instance, is intended as a ringing impulse, the impulses 125 130

before it being of specially arranged durations adapted for placing the selective apparatus at the given station in condition for making the necessary ringing connections. This however is only one of the many possible combinations. Each time the spring 14 engages the contact 16 current passes from one side of the line through the pin 23 from the rear side of the board and into the frame of the sending device, through the spring 14 into contact 16 and out through the insulated pin in the post 18 to the rear of the board and the other side of the line.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense. It is also to be understood that the language used in the following claims is intended to cover all of the generic and specific features of the invention herein described and all statements of the scope of the invention, which as a matter of language, might be said to fall therebetween.

Having thus described my invention what I claim as new and desire to secure by Letters Patent, is:

1. In a sender board apparatus, the combination with a supporting board, of a plurality of independently formed sending devices adapted to be supported upon said board, said board comprising means electrically connected with a line adapted for easily detachable engagement by the sending devices, and said means being also adapted to coöperate with the sending devices for providing insulated electrodes therefor.

2. In a sender board apparatus, the combination with a board, of a sending device to be supported thereby, a plurality of insulated supports carried by the board adapted to engage and directly support the sending device, the sending device being adapted to form electrical connection with one of said supports and to form insulated connection with another of said supports, and a pair of coöoperating electrodes one carried by said sending device and the other carried by the support which is insulated therefrom.

3. In a sender board apparatus, the combination with a board, of a sending device to be supported thereby, a plurality of insulated supports carried by the board adapted to engage and directly support the sending device, the sending device being adapted to form electrical connection with one of said supports and to form insulated connection with another of said supports, and a movable and a fixed electrode, the movable electrode being carried by the sending device

and the fixed electrode being carried by the support which is insulated from the sending device.

4. In a sender board apparatus, the combination with a board having a plurality of insulated pins projecting therefrom, of a sending device having parts adapted to be telescoped over said pins to support the sending device and to form electrical connection with one of said pins, insulating means disposed between the sending device and another of said pins, and a pair of contact members carried one by said sending device and the other by said insulated pin.

5. In a sender board apparatus, the combination with a board having a plurality of insulated pins carried thereby, of a sending device adapted to engage and be directly supported by said pins and to form electrical connection with one of said pins, insulating means disposed between said sending device and another of said pins, means for holding said sending device on said pins, a contact member held in position by said retaining means, and a coöperating contact member carried by said sending device.

6. In a sender board apparatus, the combination with a board having a plurality of insulated pins projecting therefrom, of a sending device having tubular members adapted to be telescoped over said pins for supporting the sending device and for making electrical connection between said sending device and one of said pins, an insulating member within another of said tubular members adapted for insulating said device from another of said pins, a movable contact carried by said sending device and a coöperating fixed contact carried by said insulated pin.

7. In a sender board apparatus, the combination with a board having a plurality of insulated pins projecting therefrom, of a sending device comprising parts adapted to be telescoped over said pins and to make electrical connection between said sending device and one of said pins, insulating means between said sending device and another of said pins, means for maintaining said sending device on said pins arranged to maintain said insulating means in position, a pair of contact making members carried one by said sending device and another by said insulated pin, and said retaining means serving to hold the latter contact making member in coöoperative relation with the former contact making member.

8. In a sender board apparatus, the combination with a board having a plurality of insulated supporting members projecting therefrom, of a sending device adapted to engage said supporting members so as to form electrical connection with one of said supporting members and insulated connection with another of said supporting mem-

- bers, a fixed contact making member electrically connected with the insulated supporting member, a movable contact member electrically connected with the other supporting member, and a rotary member comprised in the sending device for engaging the movable contact member to move the same into and out of a contact making relation with the fixed contact member.
- 10 9. In a sender board apparatus, the combination with a board having a plurality of insulated supporting members projecting therefrom, a sending device adapted to directly engage said supporting members and be supported thereby so as to form electrical connection with one of said supporting members and insulated connection with another of said supporting members, a pair of insulated contact making members carried 15 one by the sending device and the other by said insulated supporting member, and easily releasable means for retaining said sending device in supported relation with said supporting means.
- 20 10. In a device of the kind described, a board, a pair of pins secured therein, a sender having tubular members adapted to fit said pins, one of said pins extending through its tubular member and being secured at the opposite end thereof, one of said pins being insulated from its tubular member and thereby from the sender frame, and the other pin being in electrical connection with its tubular member and through it with 25 the sender frame, a contact connected to said insulated pin, and a recurrently coöperating contact connected with the frame.
- 30 11. In a sender-board apparatus, the combination of a board, a sending device to be supported thereby, a plurality of insulated supports carried by the board adapted to engage and support the sending device, the sending device being adapted to form electrical connection with one of said supports 35 and to form insulated connection with another of said supports, and a pair of coöperating electrodes, one electrically connected with said sending device and the other

electrically connected with the support which is insulated therefrom.

50

12. In a sender-board apparatus, the combination of a board, circuit terminals on said board, a plurality of individual call-sending devices, each having two contacts and coöperating parts on said board and each device whereby said devices may be separately and readily attached to and detached from said board, and one of the corresponding contacts of all the devices will be electrically connected to one circuit terminal, and the other corresponding contact of all the devices will be connected to another of said circuit terminals.

60

13. In a sender-board apparatus, the combination of a board having two pins insulated from each other and projecting therefrom, a sending device adapted to be supported by and readily detachable from said pins, and having two contact members, one of which is movable relative to the other, 70 one of said members being electrically connected with one of said pins, and the other of said members being electrically connected with the other pin, and means for bringing said members together.

75

14. In an impulse-sending device, the combination of a metal frame, a wheel having teeth thereon effectively corresponding to the impulses constituting its call carried by said frame, means for revolving said wheel 80 at a substantially constant speed for a single revolution for a complete call, a contact in electrical connection with said frame, and a contact insulated from said frame, said contacts being arranged to be moved into engagement with each other by the teeth on said wheel, and means whereby said frame may be easily attached to and detached from a suitable support.

85

In witness whereof I affix my signature in 90 the presence of two witnesses.

EDWIN R. GILL.
